UNITED STATES PATENT OFFICE

ERICH H. ROHL, OF CHICAGO, ILLINOIS, ASSIGNOR TO THE MANTLE LAMP COMPANY OF AMERICA, INCORPORATED

MACHINE FOR MAKING VACUUM BOTTLES AND THE LIKE

Application filed May 3, 1923. Serial No. 636,388.

The invention relates to a method and a machine for the manufacture of vacuum vessels and the like and the object of the invention is to seal the lower wall of the outer blank to the lower wall of the inner blank of a vacuum vessel.

A further object of the invention is to combine a series of units of sealing mechanisms in such manner that the six steps of operations for sealing the blanks can be easily controlled by one or two operators, thus saving considerable time and labor.

The invention will be fully understood from the detailed description hereinafter presented, reference being had to the accompanying drawings in which:

Fig. 1 is a side elevation of one unit of sealing mechanisms, parts of which being shown in section.

Fig. 2 is a diagrammatic top view of the complete machine consisting of six units of sealing mechanisms and showing the arrangement of fires and the mold.

Fig. 3 is a side elevation of the mold of the sealing machine.

Fig. 3a is a top view of the mold.

Figures 4 to 8 represent diagrammatic views of blanks of different steps of operation of which

Fig. 4 shows the inner blank of a vacuum vessel,

Fig. 5 the outer blank;

Fig. 6 shows the outer blank telescoped over the inner blank;

Fig. 7 shows the outer blank sealed to the inner blank, the dotted lines indicating the surplus glass of the blank which has been partly fused to the inner blank, partly separated from the outer blank, and

Fig. 8 shows the finished vacuum vessel, the upper walls of the inner blank being brought out of contact with the upper walls of the outer blank.

Mounted on a table 1, Fig. 1, is an electric motor 2 of a known type, by means of which rotation is transmitted to a gear 3 mounted on a main shaft 4. Shaft 4 is provided on its upper half with gears 5, 5', which are in mesh with gears 5^a, 5^b, mounted on horizontal shafts 7, 7' respectively. These shafts are

rotatably mounted on a frame structure which also is rotatably mounted upon table 1, by means of roller bearings 10, 10'. The shafts 7, 7' are provided with gears 11, 11' respectively, which are in mesh with gears 12, 12' mounted on vertical shafts 13, 13' respectively. The shafts 7, 7' are furthermore provided with friction clutches 15, 15' which are operated by levers 17, 17', these levers being respectively provided with rollers 18, 18' which come in contact with arcs 19, 19'. These arcs are arranged so as to throw out the friction clutches 15, 15', thus interrupting rotation transmitted by gears 11, 11', when desired. Shaft 13 is provided with a key 14 entering a slot in gear 12 (not shown) to permit longitudinal adjustment of this shaft without interfering with the rotation or position of gear 12. The means for longitudinally adjusting shaft 13 consists of a split nut 13^a having projecting pins 13^b. This split nut is held by threads on the lower part of shaft 13 which latter is carried by the bracket 20 mounted on frame 9. Shaft 13 furthermore carries at its upper bifurcated end an extension 21 of heat resisting material, preferably made of carbon, which serves as a support for an inner blank 22 of a vacuum vessel. Shaft 13' of gear 12' is made hollow and carries at its lower end a chuck 23, which is slotted on its sides as at 24, to permit increase or decrease of its diameter by means of a clamping ring 25. This chuck is furthermore provided with a lining 23' of heat resisting material, preferably asbestos, which material comes in frictional engagement with the outer blank 26 of a vacuum vessel inserted into this chuck. The upper part of shaft 13' is in communication with means (not shown) for introducing compressed air through this hollow shaft into the chuck for a purpose hereinafter described.

The mechanisms as explained above and illustrated in Fig. 1 of the accompanying drawings represent one unit of the sealing machine, which preferably consists of six units of like construction with the exception that five of the same do not possess a mold. These six units are connected by brackets 27, 27' mounted on the frame structure 9 and are

therefore operated simultaneously by gears 5, 5' on main shaft 4, as diagrammatically illustrated in Fig. 2.

The improved construction of a mold 28, 5 for forming the neck of the vacuum vessel is shown in Figs. 3 and 3^a and consists of two parts, 28^a, 28^b, which are pivotally connected by hinges 29' attached to the mold parts 28^a, 28^b. Slidably mounted underneath the mold 10 are rods 30, 31, having loops 32, 33 on one end, through which pins 34, 35, carried by the mold parts are projected and which pins are permitted to slide within these loops, when the mold parts are actuated. Rods 30, 31, 15 are pivotally connected at 36, while their other ends are fastened to pins 37, 38, respectively, which are slidably arranged within grooves 39, 40 of table 41, upon which the mold is mounted. A sleeve 42 is mounted on legs 42'' 20 attached to table 41, through which sleeve a shaft 43 is projected. This shaft carries on one end the hinges 29 for the mold parts 28^a, 28^b while its other end is enlarged to form a head on which a compression spring 45 acts. 25 The coil spring 45 is enclosed in a casing 46 provided for shaft 43, which casing is slid- able within sleeve 42. On each side of sleeve 42 is a slot 42' through which arms 47, 47' ex- 30 tend, these arms being fastened to the casing 46. A handlever 48 is pivotally connected to the casing 46 and is mounted upon a stand- 35 ard 49 carried by the extension 50 of table 41.

In the diagram of Fig. 2 is shown the ar- 35 arrangement of different burners and fires, 40 which are provided on five of the units for heating the lower walls of the blanks 26 and 22. A Bunsen burner B is arranged as shown at I, for the pre-heating operation. At II, III, IV and V, fires for the same purpose are 45 arranged, each fire being of a known type, having air and gas inlets, a. g, but not a part of the invention. The amount of nozzles for each fire, however, as shown in this figure, has been determined by experiments as being most effective.

To operate the sealing machine, first the outer blank of a vacuum vessel is inserted into the rotary chuck 23 and is secured therein by the action of the clamping ring 25 surround- 50 ing the slotted walls of the chuck, which ring, when pushed downward, reduces the diameter of the chuck, thus holding the outer blank in position. An inner blank of a vacuum vessel 55 then is placed over the extension 21 of shaft 13, which extension is preferably made of carbon or other heat resisting material. Then shaft 13 is raised by actuating split nut 13^a, until the inner blank of the vacuum vessel reaches the upper walls of the outer blank 26. 60 Then the friction clutches 15, 15' are thrown in by depressing levers 17, 17' to bring the gears 11, 11' into engagement. By means of the electric motor 2 rotation is then trans- 65 mitted to chuck 23, Fig. 1.

To bring each unit in the position desired

where the different steps of operation take place, handlever 9^a attached to the structure frame of each unit is pushed horizontally in counter-clockwise direction until it reaches a fork-like stop-member 9^b, which temporarily arrests the movement of the frame structure 9. This stop-member 9^b yieldingly holds handlever 9^a in position, so that the latter can be easily brought out of engagement when the frame 9 of each unit is to be pushed into another position on the table 1 for the next step of operation. When the blanks reach the position I, Fig. 2, pre-heating of the lower parts of the blanks takes place, while the same are in rotation. In positions II, III and IV 70 heating of the blanks is increased as can be seen from the increased amount of fires. In position IV the lower walls of the outer blank will become so soft under the influence of heat that the surplus amount of glass will melt 75 off, this surplus being indicated in Fig. 7 in dotted lines. The blanks are brought then into position V where in addition to the fires 80 a mold, forming a part of the sealing machine, is brought into operative position by 85 actuating hand-lever 48 the function of which will be described hereinafter.

In order to bring the mold into operative 90 position close to shaft 13, shaft 43 in casing 46 is extended by swinging hand-lever 48 in 95 a direction as indicated by an arrow in Fig. 3^a. After the shaft 43 has reached its fore- 100 most position, which is limited by a stop pin 36, resting against a fork-like stop-member 36' which is mounted on the table 41, as shown in Fig. 3, the mold parts 28^a, 28^b can be closed by the scissor-like arrangement of rods 30, 31, 105 attached to pins 37, 38 within slots of arms 47, 47' which are mounted on casing 46 and which arms are projected through slots 42' on each 110 side of sleeve 42. It is obvious that by means of pins 37, 38, sliding in the guiding grooves 39, 40, the mold parts can be closed by means of rods 30, 31, which are slidably mounted on the mold parts 28^a, 28^b. In closed position the 115 mold parts, having a hollow portion 28^c pro- 120 vided in the same, which is of the same diameter as shaft 13, surround this shaft 13, while the enlarged hollow portion 28^d surrounds the neck of the vacuum vessel. While the 125 mold is now in operative position, compressed air is introduced through the hollow shaft 13' into chuck 23 and from there through the so-called tubulation 26^a between the walls of the vacuum vessel. This pneumatic pressure serves to assist in shaping and finishing the neck of the vacuum vessel by blowing the softened glass of the lower wall portion into the form 28^d of mold 28. After giving the 130 vacuum bottle its final shape, the introduction of compressed air then is interrupted, and the mold 28 is withdrawn into inoperative position by swinging hand-lever 48 in opposite direction. Pins 37, 38 sliding in the 135 guiding grooves 39, 40 act on rods 30, 31,

thereby opening the mold parts and releasing the enclosed shaft 13 and the finished neck of the vacuum vessel, whereupon shaft 43 is entirely withdrawn, out of the path of rotation 5 of the sealing machine. The neck of vacuum vessel, still being in soft condition under the influence of fires arranged between position V and VI (not shown), reaches then the last step of operation, as indicated at VI, Fig. 2. 10 However, shortly before reaching this final position, either by hand or by some mechanical means (not shown in the drawing), the split nut 13^a is given a turn and to facilitate this operation, pins 13^b are arranged; the actuation 15 of which lowers shaft 13 for a certain length which is preferably about one sixteenth of an inch. As the inner blank 22 rests upon this shaft, it will thereby be lowered which is permitted by the softened portion of 20 its lower walls, thus coming out of contact with the upper portion of the outer blank. The entire vacuum vessel, is then in finished condition, excepting the evacuation of air between its walls, which is afterwards taken 25 care of in a well known manner. Fig. 8 illustrates the finished bottle obtained by this new process and machine. After reaching position VI, rollers 18, 18' sliding over arcs 19, 19', raise levers 17, 17', thereby throwing out 30 friction clutches 15, 15' respectively and rotation transmitted to gears 12, 12' is thus interrupted. The chuck 23 now is in at-rest position. Clamping ring 25 is then raised, thus 35 allowing the chuck to expand and to release the enclosed vacuum vessel.

In using the above described sealing machine in combination with its mold, a great saving on labor and material can be obtained, as the different steps of operation can be easily 40 controlled by one or two glass-blowers, for which, with older machines and methods, at least 4 men were needed to accomplish the same amount of work in a certain period of time. By uniting the improved mold with 45 the sealing machine, not only breakage is considerably reduced compared with older methods, where molds as tools, independent from the sealing machine were used, but, which is of still more importance, vacuum 50 vessels are obtained, the neck of which, formed by this mold, are uniform in size and shape, a very important factor in the assembly of the filler and casing, a result which cannot always be obtained by the older methods. 55

While the drawings illustrate the preferred embodiment of the invention, nevertheless various changes may be made without departing from the spirit of the invention and I, 60 therefore, do not limit myself to the constructional features as shown, but wish to avail myself of any modifications constituting departures within the scope of the invention as defined in the appended claims.

65 I claim:

1. In combination with a sealing machine, a mold, pins arranged on said mold, scissor-like means attached to said pins, pins fastened to the other ends of said scissor like means, said pins being guided within grooves arranged in the support means for said mold, and a handlever connected to the shaft of said mold. 70

2. In combination with a sealing machine, a mold, pins arranged on said mold, scissor like means attached to said pins, pins fastened to the other ends of said scissor like means, said pins being guided within grooves arranged in the supporting means for said mold, and a handlever connected to the shaft of 75 said mold, said shaft being slidably arranged within a sleeve, said sleeve being carried by a support mounted on an extension of said sealing machine. 80

In testimony whereof I affix my signature. 85
ERICH H. ROHL.
